CLAIM

The ornamental design for a foldable wireless charger, as shown and described.

DESCRIPTION

FIG. 1 is a front perspective view of a foldable wireless charger of our new design, shown in a first configuration; FIG. 2 is a rear perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is a perspective view of the foldable wireless charger, shown in a second configuration; FIG. 10 is a perspective view of the foldable wireless charger, shown in a third configuration; FIG. 11 is another perspective view of the foldable wireless charger, shown in the third configuration; FIG. 12 is an enlarged partial view of area '12' in FIG. 5; and, FIG. 13 is an enlarged partial view of area '13' in FIG. 9. The dash-dash broken lines in the drawings are for the purpose of illustrating portions of the foldable wireless charger which form no part of the claimed design. The dash-dot-dot broken lines are for the purpose of indicating the portions shown enlarged in the views and form no part of the claimed design.
